UNITED STATES PATENT OFFICE.

WALLACE B. EMMONS, OF TOLEDO, OHIO, ASSIGNOR TO DANIEL W. MILLER,
OF SAME PLACE.

HAIR-CLASP.

SPECIFICATION forming part of Letters Patent No. 565,884, dated August 18, 1896.

Application filed February 29, 1896. Serial No. 581,384. (No model.)

To all whom it may concern:

Be it known that I, WALLACE B. EMMONS, a citizen of the United States, residing at Toledo, in the county of Lucas and State of Ohio, have invented a new and useful Hair-Clasp, of which the following is a specification.

This invention relates to hair-clasps, and has for its object to provide an article of the character referred to which may be easily applied to and removed from the hair of girls and young ladies when the hair is plaited or hung loosely down the back, the said clasp being also adapted to receive a bow of ribbon or other desired ornament and hold the same out of contact with the hair and rendering it practicable to change the bows or ornaments as frequently as may be desired.

The invention consists in a hair-clasp embodying certain novel features and details of construction, as hereinafter fully described, illustrated in the drawings, and finally pointed out in the claim.

In the accompanying drawings, Figure 1 is a rear elevation of the improved clasp shown applied to a pendent braid. Fig. 2 is an elevation of the clasp, taken from the opposite side. Fig. 3 is a horizontal sectional view of the clasp applied. Fig. 4 is a detail perspective view of the clasp. Fig. 5 is a plan view of the blank of which the clasp is formed. Fig. 6 is a vertical section through the center of the clasp.

Similar numerals of reference designate corresponding parts in the several figures of the drawings.

The improved clasp is made from a sheet-metal blank of the form illustrated in Fig. 5. This blank comprises an oblong portion 1, constituting the main body of the clasp. From one side of the portion 1 projects a long strap or band portion 2, and from a point directly opposite projects a short strap or band 3. The bow of ribbon or other ornament to be employed is placed against the main oblong portion 1 of the clasp, and the short strap or band 3 is bent over to engage one end of said bow or ornament, the latter being con-

fined between the strap 3 and the body 1 and thus held securely. The long strap or band 50 2 is then bent and extended transversely across the bow or ornament, after which it is again bent and its terminal portion brought to bear against the portion 1, as shown, the bow being thus securely held. 55

The opposite ends of the oblong portion 1 are recurved to form hooks 4, and in one of said hooks is placed an elastic band or ring 5, the hook being thereafter mashed or clenched, so as to retain the elastic permanently in place. The main body portion 1 is also bent in the arc of a circle, as shown, so that it will partially embrace and to some extent conform to the shape of the plait of hair.

In applying the clasp to the hair it is placed 65 against the rear side of the plait, and the elastic band is then carried around the inside of the plait and finally engaged in the opposing hook 4. This prevents the plait from untwisting and at the same time holds the bow 70 in place. Not only this, but the bow is held out of contact with the hair and prevented from becoming soiled and unfit for use. A bow of any shape, size, or pattern may be adjusted to the clasp, and as it is not necessary 75 to form a knot in the ribbon which composes the bow such ribbon may be used repeatedly and kept clean. The clasp may of course be made of any material, such as silver, gold, &c., and be given any ornamental finish, according to the taste of the manufacturer. It is the work of an instant either to apply the clasp to the hair or to remove the same therefrom. By unbending the straps and bands 2 and 3 of the clasp the bow may be removed 85 and another one substituted therefor.

Changes in the form, proportion, and minor details of construction may be resorted to without departing from the spirit or sacrificing any of the advantages of this invention. 90

Having thus described the invention, what is claimed as new is—

A hair-clasp, comprising a curved oblong body portion having its end portions bent back to form end hooks, and also having intermediate its ends integral straps projecting 95

in opposite directions therefrom, and an elastic ring permanently connected to one of the end hooks and adapted to be passed around a plait and to detachably engage the opposing hook, said straps being capable of being bent to embrace a bow or other ornament for the hair, substantially as described.

In testimony that I claim the foregoing as my own I have hereto affixed my signature in the presence of two witnesses.

WALLACE B. EMMONS.
